UNITED STATES PATENT OFFICE.

ROBERT PHILIP KNOEBEL, JR., OF NORTH BERGEN, NEW JERSEY.

TIME-LOCK INDICATOR.

1,123,895.

Specification of Letters Patent.

Patented Jan. 5, 1915.

Application filed June 1, 1914. Serial No. 842,115.

To all whom it may concern:

Be it known that I, ROBERT PHILIP KNOEBEL, Jr., a citizen of the United States, and a resident of North Bergen, in the county of Hudson and State of New Jersey, have invented certain new and useful Improvements in Time-Lock Indicators, of which the following is a specification.

My invention is designed to afford simple but effective means whereby the locking or unlocking of a door or other closure device may be automatically announced and registered on a time basis; and the invention consists in the specific combination and arrangement of parts and appliances hereinafter described and claimed; distinctive features being a clock work driven stylus in conjunction with an actuating electromagnet interposed in an electric circuit which is temporarily closed automatically whenever the lock bolt is either sprung or retracted; the use of an annular record slip or chart formed with concentric lines of record representing successive days or cycles of time in conjunction with means for automatically shifting the stylus with relation thereto; means for suspending and supporting the clock-work centrally, and other details of construction fully set forth.

In the accompanying drawings, Figure 1, is a diagrammatical sectional view showing the essential elements of my invention; Fig. 2, a top view of the same, certain parts being omitted; Fig. 3, is a detail view of the stylus and adjacent parts, on an enlarged scale; Fig. 4, a transverse section of the stylus.

A, represents symbolically a clock-work movement of suitable character, preferably constructed to run at least ninety six hours and to rotate the stylus arm a , twice in that period of time. The clock-work A, is supported on a suspender stud or post b , pendent from a bracket arm b' , which may be attached to a box casing B, or other stationary part. The inner portion a' , of stylus arm a , is mounted upon and rigidly attached to a sleeve a^2 , fitting over a cylindrical part of the suspender stud b , and formed with a gear or pinion a^3 , meshing with a driving wheel a^4 , forming part of the clock work movement. The outer portion a^5 , of the stylus arm a , is pivotally attached to the said inner portion a' , thereof, and is held normally in alinement therewith

by a spring a^6 , which tends constantly to press the shoulder a^7 , against a corresponding shoulder on the inner portion of the arm a , as shown in Fig. 1.

The sleeve S, carrying the stylus s , is slidably mounted on the outer portion a^5 , of the arm a , being feathered or splined thereto as shown in Fig. 4, or the parts may be otherwise formed to prevent the stylus from turning laterally upon the arm while allowing it to slide longitudinally thereon. A spring s' , is arranged to tend constantly to force the stylus sleeve S, toward the inner end of the arm and hold it in contact with either the switch stop c , or the fixed stop c' . The switch stop c , is pivotally attached to the outer portion a^5 , of the arm, and when in alinement therewith, as in Figs. 1, and 2, holds the stylus sleeve S, in its most extended position against the resistance of the spring s' . When this switch stop c , is released and swung aside by the trip t , so that it extends laterally with relation to the stylus arm a , the spring s' , forces the sleeve S, inward against the fixed stop c' , as shown in Fig. 3, thereby prescribing the inner position of the stylus. The trip t , is stationary and may be mounted on top of the box casing B, or other fixed part.

M, is an electro-magnet positioned centrally under the clock-work A, with its armature m , in alinement with the suspender post b . Said armature m , is coupled to the outer portion a^5 , of the stylus arm a , by means of cord or equivalent connection sc e , in which is interposed a swivel e' , so that the stylus arm a , may rotate freely. The electro-magnet M, is interposed in an electric circuit d , d' , of which the battery D, or other source of electricity forms a part. sc The circuit is closed temporarily whenever the slidale terminal d^2 , passes and contacts with the fixed terminal d^3 . The movable terminal d^2 , is positioned on a slide h , arranged in alinement with the bolt i , of the door or other lock I, (dotted in outline in Fig. 1.) This slide h , is mounted on a plate h' , countersunk in the frame work of the door or other closure, and a spring h^2 , tends constantly to press the slide toward the bolt i , opening h^3 , in the flange h^4 . In the absence of the bolt i , the end of the slide h , rests against this flange h^4 , in position to receive the thrust of the bolt i , when the latter is shot to lock the door or closure. When the 100 105 110

slide h , is thus forced back by the bolt i , against the resistance of the spring h^2 , the movable terminal d^2 , contacts temporarily with the stationary terminal d^3 , the circuit 5 M, D, d , d' , is closed, and the armature m , attracted, thus depressing the outer end a^5 , of the stylus arm a , through the medium of the connection e , and causing the stylus s , to impinge on the annular record chart R. 10 When the bolt i , is retracted to unlock the door or other closure the spring h^2 , returns the slide h , to its normal position against the flange h^4 , again making and breaking the electric circuit so that the stylus is again 15 depressed to make a record on the dial R.

The record chart R, consists preferably of an annular strip of paper or other suitable material on the upper surface of which is printed or otherwise imposed lines representing the sub-divisions of the cycles of 20 time for which the apparatus is adapted, the names of the days, &c. This strip might be endless were it not for the fact that it has to be positioned concentrically around the 25 suspender stud b , and hence is preferably slit transversely at some point in the circle, or it may be made up of two semi-circular sections, so that it may be conveniently positioned upon and removed from the table or 30 support b^2 , which is preferably countersunk (as shown in Fig. 1,) for its reception so as to aid in centralizing and holding the chart accurately in position. In setting the apparatus the stylus sleeve S, is adjusted outward 35 against the resistance of the spring s' , and the switch stop c , turned parallel to the length of the arm a , as in Figs. 1, and 2, when the spring s' , will press the sleeve S against the end of said switch stop c , and 40 hold it in that position until the switch stop is released by the trip t . Thus positioned the stylus s , is adapted to impinge and punch the outer row r , of the sub-divisions of the chart R. When the arm a , has made 45 a complete revolution the latch stop c , encounters the trip t , and the sleeve S, assumes the inner position as above set forth, and shown in Fig. 3, bringing the stylus into alignment with the inner row r' , of sub- 50 divisions of the chart. In Fig. 2, a four day chart of this character is illustrated, each sub-division representing an hour. Obviously these sub-divisions may be further sub-divided to represent fractions of the 55 hour, and the chart may be otherwise changed or modified to meet preference or requirements of use, it being understood that the chart R, is so positioned on its support as related to the trip t , that the latter 60 will effect the change of stylus from the

outer concentric row r , to the other inner r' , at the appropriate time.

The support b^2 , for the chart R, may be formed with annular grooves b^3 , b^4 , (Fig. 3,) coincident with the two positions of the 65 stylus s , to facilitate the indentation or puncture of the record by the stylus, where the latter is pointed for the purpose; or a stylus adapted to otherwise mark the record R, may be substituted for that shown if preferred. 70

A bell m' , or other sounding device to be actuated by the armature m , may be provided to announce the bolting or unbolting of the door or closure simultaneously with 75 the recording of the fact.

What I claim as my invention and desire to secure by Letters Patent is,

1. In recording apparatus of the character designated, a suspended clock movement, 80 a depressible stylus rotated thereby, a concentric time chart, an electric-magnet positioned under said clock movement in alignment with its suspender support, an armature for said magnet, a connection between 85 said armature and said stylus arm, an electric circuit in which the magnet is interposed, and a slidable contact forming part of said electric circuit and adapted to be actuated by a closure lock bolt to make and 90 break the circuit, for the purpose described. 90

2. In recording apparatus of the character designated, a suspended clock movement, 95 a depressible stylus arm rotated thereby, a concentric time chart formed with concentric rows of time spaces, a stylus sleeve slidably mounted on said arm, a spring on said arm, contacting with said stylus sleeve, a stationary stop on said arm for contacting with the stylus sleeve, a switch stop pivotally mounted on said arm and adapted to contact with said stylus sleeve, a stationary trip arranged to move said switch stop out of engagement with the stylus sleeve when the arm passes under said trip, an electro-magnet positioned under said clock movement in alignment with its suspender support, an armature for said magnet, a connection between 100 said armature and said stylus arm, an electric circuit in which the magnet is imposed, and a slidable contact forming part of said electric circuit and adapted to be actuated by a closure lock bolt to make and break the circuit, for the 105 purpose described. 110
